UNITED STATES PATENT OFFICE.

CHRISTIAN HENRICHSEN, OF PITTSFIELD, MASSACHUSETTS, ASSIGNOR TO GENERAL ELECTRIC COMPANY, A CORPORATION OF NEW YORK.

ARC-LAMP.

1,152,731.

Specification of Letters Patent.

Patented Sept. 7, 1915.

Application filed October 11, 1912. Serial No. 725,124.

To all whom it may concern:

Be it known that I, CHRISTIAN HENRICHSEN, a subject of the King of Denmark, residing at Pittsfield, in the county of Berkshire, State of Massachusetts, have invented certain new and useful Improvements in Arc-Lamps, of which the following is a specification.

My invention has reference to an arc lamp, and more particularly to a method and apparatus for correcting the magnetic action upon the arc of the current which is conducted through the side rod past the arc. When an arc is formed between vertically aligned electrodes, the arc current is either conducted to the upper electrode when the upper electrode is the positive and when the current is direct current and through the arc to the lower electrode; or in case the lower electrode is the positive, the direction of the current is reversed. In either of these cases and also when alternating current is used, it becomes necessary to conduct the arc current past the arc, and this current exercises a magnetic repelling effect upon the arc, driving the same to the sides of the electrodes remote from the conductor which carries the current, thereby causing the arcing faces of the electrodes to burn slanting, and this results in objectionable shadows and also causes the arc to rupture with too great frequency, and in general results in unsatisfactory operation of the lamp. I overcome these difficulties by so passing the current to and from the electrodes as to neutralize the blowing effect of the current in one conductor by the current in other conductors, all suitably arranged with reference to each other and to the arc.

My invention has as a further object a novel arrangement of conductors for leading the current from the side rod to the lower electrode, whereby the blowing action which results from the current in the side rod toward the end of the life of the lower electrode is avoided.

While my invention is applicable to any arc lamp where the evil of side-burning of the arc exists, it is particularly useful in conjunction with flaming arcs, as such arcs are long and rather slender and are easily influenced by external conditions. Moreover, as practically all of the light is emitted from the arc itself instead of an incandes-

cent tip, it is obvious that the shadows resulting from tapered electrodes are particularly pronounced and objectionable.

For a fuller understanding of my invention reference is had to the accompanying drawings, in which—

Figure 1 is a side elevation of a portion of an arc lamp embodying my invention, and Fig. 2 is a sectional plan view on the line 2—2 of Fig. 1.

In the drawings 1 and 2 are the upper and lower electrodes, respectively. The upper electrode passes through and is guided by an economizer 3 of usual form and also through the bottom plate 4 of the lamp. The lower electrode 2 is carried by a pair of arms 6, 7 which extend somewhat slantingly toward the electrode from the lower end of the side rod 5. These arms 6, 7 extend partially around the lower electrode and are electrically connected thereto through plates 8 and 9 within which the lower electrode is clamped. With lamps such as have hitherto been commonly used, the current in the side rod is conducted therefrom away from the lamp and the current in this side rod blows the arc to that side of the electrodes remote from the side rod, thereby causing the arcing faces of the electrodes to become slanting and bringing about the unsatisfactory operation referred to above. Instead of conducting the current immediately away from the lamp, as it leaves the side rod, I lead the current downwardly through a flexible connection 10 to a conductor 11 arranged substantially parallel to the side rod 5 and adjacent thereto and preferably immediately behind the side rod 5, as I find that this is the most satisfactory arrangement. From the lower end of this conductor, the current passes in two substantially equal branches through a ring 12 surrounding the arc and a conductor 13 connected to the opposite side of the ring from the conductor 11, from which the current is conducted from the lamp in the usual way. The conductor 11 is thus arranged in series with the conductor 5 and the current passing through the same passes in the opposite direction from the current in the conductor 5, thereby largely or wholly neutralizing the magnetic action of the current in the conductor 5. The conductor 13 is so arranged with reference to its distance from the electrodes and to its distance above

100
105

the arcing face of the lower electrode as to off-set whatever resulting blow from the two conductors 5 and 11 may exist. In the construction which I have here shown in which 5 the plane of the ring 13 passes through the arc, the action of the current passing through the two branches of the ring is neutral with reference to the arc.

When inclosing globes more or less conical in form, such as are commonly used with 10 flame lamps of this character, are employed, the side rod at the lower end, or the arm which is secured to the bottom of the side rod, is necessarily inclined downwardly to 15 ward the electrode in order to bring the point of support for the electrode sufficiently below the arc to accommodate an electrode of the required length and at the same time to cause the lower end of the side rod or the 20 arm secured thereto to conform to the shape of the globe. Under these circumstances, when the lower electrode is nearly consumed and the inclined lower end of the side rod is brought opposite to the arc, the current 25 in the inclined portion of the side rod is necessarily nearer the arc than is the current in the vertical portion of the side rod under normal conditions, with the consequence that the current exercises a stronger 30 magnetic action on the arc than normally, and the arc is driven to the opposite sides of the electrodes. I have overcome this difficulty by conducting the current from the side rod to the lower electrode through two 35 branches or arms which extend partially around the electrode, thereby obviating the repelling action, which would be caused by the current in a single conductor inclined downwardly toward the lower electrode.

40 While I have illustrated in the drawings what I consider to be the best embodiment of my invention, it is obvious that the same is susceptible of various modifications without departing from the spirit thereof.

45 What I claim as new and desire to secure by Letters Patent of the United States, is:—

1. In an arc lamp, a pair of axially alined electrodes between which the arc is formed, a conductor adapted to carry the arc current 50 past the arc, a second conductor arranged parallel and adjacent to said first conductor and connected in series therewith, and a conductor arranged substantially parallel to said first conductor on the opposite side of the arc

therefrom and electrically connected to said 55 second conductor.

2. In an arc lamp, a pair of axially alined electrodes between which the arc is formed, a conductor adapted to carry the arc current past the arc, a second conductor arranged substantially parallel and adjacent to said first conductor and connected in series therewith, a third conductor substantially parallel to said first conductor but on the opposite side of the arc therefrom, and 60 a conducting ring inclosing the axis of the electrodes connected to the second and the third conductors.

3. In an arc lamp, a pair of axially alined electrodes between which the arc is formed, 70 a conductor adapted to carry the arc current past the arc, a second conductor arranged substantially parallel and adjacent to said first conductor and connected in series therewith, a third conductor substantially parallel to said first conductor on the opposite side of the arc therefrom, and a conducting ring surrounding the arc electrically connected to the second and the third conductors. 75

4. In an arc lamp, a pair of axially alined electrodes between which the arc is formed, a conductor adapted to carry the arc current past the arc and two arms electrically connected to said first conductor and to the 80 lower electrode and inclined downwardly from the bottom of said conductor and passing partially around said electrode.

5. In an electric arc lamp, a pair of electrodes, one of which has its arcing face 90 above that of the other, a conductor adapted to carry the arc current past the arc on one side thereof, a second conductor adjacent to said first conductor and connected in series therewith to partially neutralize the 95 blow effect of the first conductor upon the arc, a third conductor in the arc circuit on the opposite side of the arc for neutralizing the residual blow effect, and a conductor in a neutral position connecting the conductors of the two sides. 100

In witness whereof, I have hereunto set my hand this 8th day of October, 1912.

CHRISTIAN HENRICHSEN.
